UNITED STATES PATENT OFFICE.

CHARLES C. SADLER, OF ALTOONA, PENNSYLVANIA.

SAND OR ABRASIVE PAPER HOLDER.

No. 905,464.

Specification of Letters Patent.

Patented Dec. 1, 1908.

Application filed June 10, 1907. Serial No. 378,260.

To all whom it may concern:

Be it known that I, CHARLES C. SADLER, a citizen of the United States, residing at Altoona, in the county of Blair and State of Pennsylvania, have invented certain new and useful Improvements in Sand or Abrasive Paper Holders, of which the following is a specification, reference being had therein to the accompanying drawing.

10 This invention relates to improvements in sand or abrasive paper holders, the main object being to provide a new and novel holder, whereby sand paper is quickly removed when worn, and replaced by a simple and efficient means, which clamps the sand paper in a rigid and taut position upon the holder, without the necessity of using glue or any but mechanical means.

To carry my invention into practice, I 20 employ a device, which is adapted to receive a portion of the holder, and have the sheet of sand paper placed therein, the holder being so arranged with relation to the device, as to have the smooth surface of the paper 25 in contact therewith. By means of a concentric means, clamping devices are so operated as to push the holder forward into closer contact with the device, while the portion of the holder is clamped tightly against 30 the holder, stretching the sand paper and securing it upon the holder. The device is now removed from the holder, and the paper is ready for use.

To more clearly illustrate my invention, 35 attention is invited to the accompanying drawings, in which:—

Figure 1 is a rear plan view of the preferred form of my sand paper holder. Fig. 2 is a central section thereof, before the sand 40 paper has been tightened in the holder. Fig. 3 is a similar view with the paper tightened. Figs. 4 and 5 are detail views of the clamp. Fig. 6 is a detail section illustrating the angles between the disk and rim. Fig. 7 is a 45 rear plan view of a modified form of holder. Fig. 8 is a cross section thereof with the paper in position before tightening, and Fig. 9 is a similar view with the paper taut.

Referring to the drawings:—The numeral 50 1 designates the holder or disk, which is secured to a lathe or other revolving medium by means of the circular lug or boss 2. Secured to the rear face of the disk near the periphery thereof is a metal ring 3, which 55 has connected thereto the sliding concentric ring 4, through the medium of the pins 5,

which are carried by the ring 4, and pass through the curved slots 6, of the eccentric clamps 7, which are secured pivotally to the stationary ring 3, by means of the bolts or 60 screws 8. In order to secure the sand paper upon the outer face of the holder, the eccentric surfaces 9, of the clamps 7, are thrown into engagement with the underface of the projecting rim 10, of the clamping band or 65 ring 11, and thus draw the clamping band, toward and over the curved periphery or edge 12 of the holder, and thus stretch the sand paper and secure the turned edges thereof between the clamping band and the 70 edge of the holder. It will be noticed by reference to Fig. 4 that the angle α of the edge 12 is about 65 degrees, while the angle β of the clamping rim 11, of the band is 60 degrees, thus providing a difference which 75 allows the edges of the sand paper to be securely gripped at all points throughout the holder.

In Figs. 7, 8 and 9, I have illustrated a 80 modified form of holding device, which embodies a centering and securing device with the holder. This device consists of a holding disk or plate 19, which has slidingly mounted upon its rear face near its periphery the concentric ring 20, which is held in 85 its relative position to the disk 19, by means of the securing devices 21. Adapted to be used in conjunction with the disk 19 to hold the sand paper upon said disk, is a clamping band 22, which has the paper gripping 90 inclined surface 23, which is adapted to surround the inclined peripheral edge 24 of the disk 19. In securing the sand paper to the face of the disk 19, the paper is inserted in the band rough surface down, and so 95 that its edges project against the surface 23 thereof. The disk 19, is then inserted, the pins or studs 25, carried by the ring 20 passing through the notches 26 of the band and seating within the internal annular 100 groove or channel 27 of the band. The ring 20, is then turned, the pins or studs 25, being thrown into engagement with the lower inclined or eccentric face of the curved plates 28, which force or move the disk 19 further 105 within the band, so that the crimped or turned up edges of the sand paper is gripped tightly between the surface 23 and edge 24, thus securely holding the sand paper in place. In order that the concentric rings 4 110 and 20, respectively, may be turned to fasten or unfasten the clamping bands of

the respective holders, I provide the lugs *c* and *d*, respectively, which are adapted to be engaged by a spanner.

What I claim, is:—

- 5 1. A holder for sand or abrasive paper, comprising a disk adapted to receive the paper, a band adapted to surround the disk and have the edge of the paper between it and the edge of the disk, a sliding ring carried by the disk, and wedging means operably connected with said ring and adapted to be introduced between the band and disk to clamp the edge of the paper between the band and the edge of the disk.
- 15 2. A holder for sand or abrasive paper, comprising a disk adapted to receive the paper, a band adapted to surround the disk and have the edge of the paper between it and the edge of the disk, a ring mounted upon the disk so as to slide slightly concentrically, and pivoted eccentrics operated to

be wedged between the band and disk as the ring is moved to draw the clamping portion of the band toward the edge of the disk.

3. A holder for sand or abrasive paper, 25 comprising a disk adapted to receive the sand paper, a band adapted to surround the disk and clamp the edge of the paper between the band and rim of the disk, a ring sliding concentrically upon the disk, and a 30 series of wedges pivoted to the disk and having handles connected to the ring, whereby as the ring is moved the wedging ends of the wedges are forced between the disk and band to cause the band to clamp the edge of 35 the paper firmly upon the disk.

In testimony whereof I affix my signature in presence of two witnesses.

CHARLES C. SADLER.
